CLAIM

The ornamental design for a scarf, as shown and described.

DESCRIPTION

FIG. 1 is a front elevational view of a scarf showing my new design, the rear is a mirror image thereof, the broken away portion is for ease of illustration;

FIG. 2 is a front elevational view of a second embodiment, the rear is a mirror image, the difference being the shape of the leaf pattern, the broken away portion is for ease of illustration; and,

FIG. 3 is a front elevational view of a third embodiment, the rear is a mirror image, the difference being the shape of the grape and leaf pattern.

FIG. 3

FIG. 2

FIG. 1
